UNITED STATES PATENT OFFICE

CHARLES J. SAGEBRECHT, OF BROOKLYN, NEW YORK, ASSIGNOR TO INTERSTATE
ELECTRIC NOVELTY CO., OF NEW YORK, N. Y., A CORPORATION OF NEW YORK.

PORTABLE ELECTRIC FLASH-LIGHT.

1,187,555.

Specification of Letters Patent. Patented June 20, 1916.

Application filed January 22, 1914. Serial No. 818,616.

To all whom it may concern:

Be it known that I, CHARLES J. SAGEBRECHT, a citizen of the United States, and a resident of Brooklyn, in the county of 5 Kings and State of New York, have invented certain new and useful Improvements in Portable Electric Flash-Lights, of which the following is a specification.

The invention pertains more particularly 10 to improvements in the class of electric lamps designed to be held in the hand and sometimes used as flash lights and at other times for affording a permanent light for a short period, and the object of the invention is to provide a new construction and arrangement of the tubular shell or casing of the flash light or lamp and of the conductor which extends lengthwise of said shell or casing to be engaged by the circuit closing means, whereby the said conductor is 15 permanently protected within the wall of the shell or casing against any action that the battery might otherwise have on it and whereby also the circuit closing means may 20 be located at a point above the battery where usually abundant space is left and in this instance utilized to receive the contacts of the circuit closing means, the circuit closing means in accordance with my invention 25 preferably comprising an exterior button-head to be operated transversely of the exterior shell or casing and carrying two contact members to respectively engage the conductor embedded within said shell or 30 casing and the metal reflector for the lamp when it is desired to complete the circuit and effect the lighting of the lamp. A reverse movement of the buttonhead serves to break the circuit through the lamp.

40 In carrying out my invention I use a single conductor extending lengthwise of the exterior shell or casing and embedded therein instead of the two conductors which are ordinarily employed in this class of lamps, 45 and embed this conductor within the material of the shell or casing where it is protected against any destructive action of the battery either by the movement of the battery during its insertion and withdrawal or 50 by corrosive action, and the life of the lamp is thereby greatly extended.

55 My invention resides in the novel construction and arrangement having to do with the conductor embedded within the shell of the exterior casing and in the circuit

closing means coöperating therewith, the lens, lamp, reflector, battery and metal end caps being of usual or any suitable form and construction.

The invention will be fully understood 60 from the detailed description hereinafter presented, reference being had to the accompanying drawings, in which:

Figure 1 is a side elevation of a portable electric flash light or lamp embodying my 65 invention, the operating buttonhead of the circuit closing means being illustrated in the position it has when the circuit is open; Fig. 2 is a vertical section through the same; Fig. 3 is a sectional view through the upper 70 portion of the exterior shell or casing taken at right angles to the section of Fig. 2 and looking inwardly at the contacts of the circuit closing means, said contacts being shown as having been moved to their operative 75 position; Fig. 4 is a vertical section through a portion of the shell or casing taken on the dotted line 4-4 of Fig. 3 and designed to illustrate the conductor embedded within 80 said shell and the engagement of one of the contacts of the circuit closing means with the upper inwardly bent end thereof; Fig. 5 is a horizontal section on the dotted line 85 5-5 of Fig. 2 illustrating the circuit closing means in position closing the circuit; Fig. 6 is a corresponding view showing the circuit closing means in their inoperative 90 position or the position said means occupy when the lamp is not in use or the circuit is open; Fig. 7 is a view, partly in section, 95 illustrating the method of constructing the exterior shell or casing of the lamp with the conductor embedded therein, and Fig. 8 is a vertical section, partly broken away, through the exterior shell or casing and 100 illustrating the full length of the conductor embedded therein, said conductor at its ends being exposed for electrical connection with other parts of the lamp.

In the drawings, 10 designates the exterior shell or casing, 11 the battery, 12 the lens, 13 the electric lamp-bulb, 14 the metal reflector for said bulb, 15 the electric connection of the battery with the lamp, and 16 the usual electrical conductor connection 105 between the metallic cap 17 and the lower terminal of the battery 11, said battery, lens, lamp-bulb, reflector, electric connections 15, 16, and cap 17 being of customary character.

Embedded within the wall of the shell or casing 10 is the conductor 18 extending substantially the entire length of said shell or casing and being a metal strip having its upper end bent inwardly and downwardly to form a contact 19 and its lower end bent outwardly and upwardly to form a contact 20. The shell 10 is recessed, as at 21, to permit the upper end of the conductor 18 being bent inwardly and downwardly, and is also recessed, as at 22, to permit the lower end of the conductor 18 being bent outwardly and upwardly.

In the regular manufacture of the shells or casings 10, the conductor 18 will extend the full length thereof, and hence it is necessary that the recesses 21, 22 be formed in the end portions of the shell or casing so as to expose the ends of the conductor 18 and permit said ends to be fashioned into the contacts 19, 20. The lower contact 20 is in electrical engagement with a threaded metal sleeve 23 secured upon the lower end of the shell 10 and engaged, as usual, by the metal cap 17.

Upon the upper end of the shell or casing 10 is secured a metal sleeve 24, and mounted upon the upper inturned edges of this sleeve is the customary reflector 14 which has a flanged upper edge to seat on the flange at the upper edge of said sleeve. On the reflector is placed the lens, and the lens and reflector are firmly secured in position by means of an upper cap or sleeve 25 which is ordinarily screw-threaded and engages a thread on the sleeve 24.

The shell or casing 10 is made from a sheet or strip of paper, fiber or other non-conducting material wound, also upon layer, on a mandrel whose diameter is equal to the bore of the shell or casing to be produced, the sheet or strip being continuous and wound around the mandrel until the requisite thickness in the tube has been secured. In accordance with my invention, during the winding of the sheet or strip to form the tube or shell 10, I apply between two of the layers, as wound, a strip of metal extending lengthwise of the tube, as represented in Fig. 5, and this metal strip during the formation of the tube becomes embedded therein and is finally converted into the conductor or conductors 18. I will ordinarily use a continuous metal strip and form a tube of sufficient length to be cut into a suitable number of sections for the formation of the shells or casings 10. After a tube of proper length and thickness has been formed and has had embedded or enveloped in it a conducting strip extending the full length of the tube, the latter will be cut transversely into the requisite lengths for the shells or casings 10, one of which is illustrated. Ordinarily electric lamps of the class to which my invention

pertains have, in lieu of my one conductor 18, two conductors extending inwardly from opposite ends of the shell to the circuit closing means, and heretofore these conductors have been exposed at the inner surface of the shell or casing 10 and were directly engaged by the shell or casing of the battery. In accordance with my invention I protect the conductor against exposure to the action of the shell of the battery and make use of a single conductor in lieu of the two conductors heretofore customarily employed.

The shell or casing 10 is, as will be understood from the drawings, a stiff hard shell of sufficient thickness and strength to permit its use for the purposes described. The shell is capable of withstanding considerable strain as is necessary in the use to which it is placed. If the shell were not self sustaining, hard and strong it would be unsuitable as a casing for a flash light. The material of the shell is exceedingly dense, and in the practice of my invention said shell or casing has been made of fiber.

The circuit closing devices comprise a metal plate 26 having spring contact fingers 27, 28, respectively, and a buttonhead 29 having a stem 30 extending through a slot 31 formed in the wall of the shell 10 and secured to said plate 26. The plate 26 is formed on the curvature of the inner wall of the shell or casing 10 so that it may conveniently slide on said wall either in one direction or the other when moved by the buttonhead 29 to its operative or inoperative position. The slot 31 is preferably inclined so that when the buttonhead 29 is moved from its inoperative position shown in Fig. 1 to its operative position shown in Fig. 3, the plate 26 will be slightly elevated so as to carry the contact finger 27 thereof not only laterally toward the conductor 18 but upwardly so as to assuredly effect an efficient engagement of said finger with the downwardly bent end or contact 19 of said conductor 18. The contact finger 28 of the plate 26 is in electrical connection with the reflector 14, as clearly illustrated in Figs. 5 and 6. When the contact finger 27 is out of electrical connection with the contact 19 of the conductor 18, the circuit is open even though the contact finger 28 may be in contact with the reflector 14, but when by means of the buttonhead 29 the plate 26 is moved to carry the contact finger 27 into engagement with the contact 19 of the conductor 18, the circuit through the lamp will be closed, as is obvious, and the lamp will be lighted. When the buttonhead 29 is again moved to its inoperative position the contact finger 27 will be disengaged from the contact 19 of the conductor 18 and the circuit through the lamp will be broken. It may be seen on reference to Fig. 2 that the circuit closing means are wholly above the battery 11 and

in a commodious space which in the class of electric lamps to which my invention pertains is ordinarily not occupied, and the utilization of the space above the battery 11 5 enables me to locate the contact fingers wholly within the shell or casing 10 and obviates the necessity of providing on the exterior of said casing the usual contacts and housing therefor customarily employed 10 on tubular electric lamps having conductors extending inwardly from the opposite ends of the casing. My invention permits of the transverse movement of the circuit closing means and obviates any necessity for leaving anything projecting beyond the casing other than the buttonhead by which the 15 circuit closing means may be manually operated.

It is believed that the utility and advantages of the invention will be fully recognized from the foregoing description and therefore that further detailed explanation is not necessary.

What I claim as my invention and desire 25 to secure by Letters Patent, is:

1. In an electric flash light of the class described, a non-conducting shell or main casing, a conductor extending in one continuous piece substantially the entire length 30 of the shell, a lamp and reflector on one end of said shell, a battery within the shell in electrical connection with the lamp and the lower end of said conductor, and manually operative circuit closing means for connecting the other end of said conductor in the 35

lamp and battery circuit for completing the same, said circuit closing means comprising a plate having an exposed head to be manually engaged and two contact fingers one to engage a downwardly bent upper end of 40 said conductor and the other the lamp reflector.

2. In an electric flash light of the class described, a non-conducting shell or main casing, a conductor extending in one continuous piece substantially the entire length of the shell, a lamp and reflector on one end of said shell, a battery within the shell in electrical connection with the lamp and the lower end of said conductor, and manually 45 operative circuit closing means for connecting the other end of said conductor in the lamp and battery circuit for completing the same, said circuit closing means comprising a plate having an exposed head to be manually engaged and two contact fingers one to engage a downwardly bent upper end of 50 said conductor and the other the lamp reflector, and said shell having a transverse upwardly inclined slot to permit the movement of said head and cause said fingers to move upwardly during their transverse movement to close the circuit.

Signed at New York city, in the county 55 of New York and State of New York this 60 9th day of January, A. D. 1914.

CHARLES J. SAGEBRECHT.
